UNITED STATES PATENT OFFICE.

OTTO WILHELM BACH, OF ELLENSBURG, WASHINGTON.

WINDOW-SHADE OPERATOR.

Application filed April 28, 1927. Serial No. 187,345.

This invention relates to devices for operating window shades where the shade is not provided with a spring roller and the general object of the invention is to provide a very simple, readily applied and effective device of this character by which a window shade may be raised to any height desired and held in this raised position and without the use of cords or like contrivances.

10 My invention is illustrated in the accompanying drawings, wherein:—

Fig. 1 is a face view of a window with my shade operating device applied thereto;

Fig. 2 is an elevation of the shade operating device;

Fig. 3 is an end view of the roller gudgeon;

Fig. 4 is an elevation of the case with the side plate removed;

20 Fig. 5 is an elevation of the side plate;

Fig. 6 is a section on the line 6—6 of Fig. 2.

Referring to these drawings, 10 designates one side section of an elongated metallic 25 casing and 11 the opposed side section. The section 10 has an inclined wall 12 at one end and a side wall 13 extending around nearly the remainder of the section. Disposed adjacent one end of this wall but inward there- 30 of is a relatively short wall or flange 14. The section 11 is adapted to fit within the peripheral wall of the section 10. The section 10 is formed with a series of sleeves or collars 15 which act as spacing sleeves 35 holding the section 11 in spaced relation to the section 10. The section 10 has a plurality of screws 16 projecting therefrom adapted to pass through the collars 15 and headed at their extremities so as to hold the 40 section 11 upon the section 15 and form a case. Any other suitable means for forming this case may be used.

45 Adjacent the end of the case remote from the inclined wall 12 there are formed the apertures 17 in sections 11 and 10. The gudgeon 18 is rotatably mounted in these apertures and has a many sided portion 19 projecting beyond the outer face of the case and adapted to be engaged with a window shade roller. The gudgeon carries upon it the gear wheel 20. Mounted upon the sleeve 15 which is remote from the gudgeon 18 is a segment gear 21 having an arm 22 projecting out tangentially therefrom. This 50 segment gear engages with a gear 23 which forms one or a train of gears whereby oscil-

lation of the segment gear 21 is communicated to the gear 20. The gears of this train of gears are all numbered 23. The gears are of such sizes and ratios that when 60 the segmental gear is given an oscillation through one hundred and eighty degrees, the driving shaft or gudgeon 18 will be given about eighteen revolutions or more according to the length of the shade desired 65 to be operated. Quite obviously the number of gears may be reduced and different proportions used for the gears so as to increase or decrease the number of revolutions given to the gear 20 upon the partial revolution 70 given to the gear wheel 21. Preferably the gear wheels 23 will be double gear wheels that is, each will have a relatively large toothed portion and a relatively small or pinion-like toothed portion as shown in Fig- 75 ure 6, so as to secure this multiplication of the number of revolutions transmitted from one wheel to the other. These gear wheels are mounted upon the sleeves 15 for rotation therearound.

80 Pivottally engaged with the arm 22 is a link or handle 24 which depends from the extremity of the arm 22. When the arm 22 is in a vertical position, it bears against the flange 14 which thereby constitutes a 85 stop and the link 24 will hang straight downward adjacent the edge of the case. Under these circumstances the shade will be fully raised. When it is desired to lower the shade, the link may be pulled downward 90 to any desired extent. It is obvious that the shade may be raised by pulling downward upon the link and lowered upon the reverse movement. The arm 22 just fits between the two sections 10 and 11 of the case so that 95 the frictional engagement of these two side pieces will act to hold the arm in its adjusted position.

100 The upper end of the case is formed with two apertures 25 and the lower end of the case is formed with a single aperture 26 through which screws may be passed to hold the case to the window frame. By tightening up upon these screws, the two sides of the case may be forced toward each other 105 to a greater or less extent and thus the frictional engagement with the arm 22 may be increased or decreased. Obviously the gudgeon as shown in Fig. 6, will be used in connection with a cap 26 on the end of the shade 110 roller having an oblong opening or socket therein into which the gudgeon may pass,

(see Fig. 3) but on the other hand, it is obvious that the gudgeon or shaft 18 may be formed with a socket to receive a gudgeon upon the extremity of the shade roller.

5 Many changes might be made in the details of construction without departing from the spirit of the invention as defined in the appended claims.

I claim:—

10 1. An operating device for window shades comprising a casing consisting of two parallel members, one of said members having spacing sleeves, a train of multiplying gears mounted upon the spacing sleeves and intermeshing with each other, the first gear of the train being formed of a segment gear and having a tangentially extending arm, a link pivoted to said arm whereby the segment gear may be operated, the last gear 15 of the train having a shaft extending through said casing and formed for rotative engagement with a window shade.

2. An operating device for window shades comprising a casing consisting of two parallel members, one of said members having spacing sleeves, a train of multiplying gears mounted upon the spacing sleeves, and intermeshing with each other, the first gear of the train being formed with a segment gear 25 and having a tangentially extending arm, a link pivoted to said arm whereby the segment gear may be operated, the last gear of 30

the train having a shaft extending through said casing and formed for rotative engagement with a window shade, one edge wall 35 of the casing being open to permit the arm to be disposed within the casing, there being a stop limiting the inward movement of the arm.

3. An operating device for window shades 40 comprising a casing consisting of two parallel members, one of said members having spacing sleeves, a train of multiplying gears mounted upon the sleeves and intermeshing with each other, the first gear of the train being formed with a tangentially extending arm, the casing having a longitudinally extending stop inward of its front edge against which said arm will bear when the arm is in a vertical, upwardly extending position, and a straight link pivoted to the outer end of said arm and extending parallel to the arm and the casing when the arm is in its retracted, upwardly extending position, said link constituting means whereby the arm and the train of gears may be operated, the last gear of the train having a shaft extending through said casing and formed for rotative engagement with the window shade.

55 In testimony whereof I hereunto affix my signature.

60 OTTO WILHELM BACH.
